UNITED STATES PATENT OFFICE.

ROBERT G. CORNFORTH, OF SEYMOUR, CONNECTICUT, ASSIGNOR OF ONE-HALF TO FRANK H. BEECHER, OF SAME PLACE.

REAR-FORK END FOR BICYCLES.

SPECIFICATION forming part of Letters Patent No. 587,933, dated August 10, 1897.

Application filed March 9, 1897. Serial No. 626,646. (No model.)

To all whom it may concern:

Be it known that I, ROBERT G. CORNFORTH, a citizen of the United States, residing at Seymour, in the county of New Haven and State 5 of Connecticut, have invented certain new and useful Improvements in Rear-Fork Ends for Bicycles; and I do hereby declare the following to be a full, clear, and exact description of the invention, such as will enable others 10 skilled in the art to which it appertains to make and use the same.

My invention relates to rear-fork ends for bicycles, and has for its object to produce a socket for the adjusting-screw which shall be 15 formed by making transverse cuts in the blank and pressing the strip of metal between the cuts in one direction and the strips outside of the cuts in the opposite direction to form loops which comprise the socket.

With this end in view I have devised the novel rear-fork end which I will now describe, referring by reference-characters to the accompanying drawings, forming a part of this 20 specification, in which—

Figure 1 is an elevation, and Fig. 2 an edge view, of so much of a rear-fork end for bicycles as is necessary to illustrate my present invention; and Fig. 3 is a view the reverse of Fig. 1 and showing the adjusting-screw placed 25 centrally of the rear-fork end instead of upon one side, as in Figs. 1 and 2.

A denotes the blank from which my novel rear-fork end is formed. The blank is struck out and formed from sheet metal and comprises a body 1, having a slot 2 to receive one 30 end of the axle and arms 3, the continuations of which (not shown in the drawings) serve as the tube connections. These tube connections are not shown in this application, as they 35 form no portion of my present invention. I preferably use, however, in connection with my novel adjusting-screw socket the tube connections described and claimed in the pending application of Frank H. Beecher and myself, Serial No. 602,859, filed August 15, 1896.

C denotes the ordinary adjusting-screw. The socket which receives this screw is made wholly from the metal of the fork end itself, no additional parts being required, and consequently no riveting or brazing. I form the 50 socket by simply making two transverse cuts 8 in the blank and then pressing the strip of metal 9 between the cuts in one direction and pressing the strips 10 outside of the cuts in the opposite direction, thus forming three 55 loops which together comprise the socket, which is threaded to receive the adjusting-screw, the position of the adjusting-screw relatively to the fork end being determined by the position of the loops which comprise 60 the socket. This socket may be formed by pressing either strip 9 or strips 10 outward farther than the other strips. In Figs. 1 and 2 I have shown strip 9 as pressed outward farther than strips 10, so as to place the socket 65 at one side of the rear-fork end, and in Fig. 3 I have shown strips 10 as pressed in one direction the same distance that strip 9 is pressed in the opposite direction, so that the socket is formed approximately at the center 70 of the rear-fork end.

Having thus described my invention, I claim—

A rear-fork end for bicycles formed from a blank of sheet metal and having an adjusting-screw socket formed by making transverse cuts in the blank and pressing the strip of metal between the cuts in one direction and the strips outside of the cuts in the opposite direction to form loops which comprise 80 the socket, substantially as shown and described.

In testimony whereof I affix my signature in presence of two witnesses.

ROBERT G. CORNFORTH.
